Specification of Letters Patent. Patented Aug. 23, 1910.

Application filed August 21, 1909. Serial No. 513,987.

To all whom it may concern:

Be it known that I, HERSCHEL DORSEY SPENCER, a citizen of the United States, residing at Boston, in the county of Suffolk 5 and State of Massachusetts, have invented certain Improvements in Presses, of which the following description, in connection with the accompanying drawings, is a specification, like reference characters on the 10 drawings indicating like parts in the several figures.

This invention relates to presses in which the presser members are relatively movable into different operative relations to each 15 other, and particularly to presses of the type employed to cut out thin sheet material such as upper leather for boots or shoes.

Presses of the type just referred to are advantageously constructed with presser members having different pressure surface areas, and in a preferred construction a movable presser member having a pressure surface area considerably less than that of the opposed stock supporting bed is movable over 25 said bed to bring it into operative relation to a die placed upon different portions of the stock to be cut which is supported upon the bed, this movement being preferably provided for by arranging the member so 30 that it swings about a vertical axis at one side of the bed.

The movement of the presser member into operative relation to the die may be effected in any suitable manner, as, for example, by 35 hand, but in order that the machine may have as great capacity as possible, it is desirable that the pressing operation take place immediately after the presser member comes into operative position. Provision 40 has been made in known machines for this succession of operations. It has been found, however, in practice that, if the pressing operation takes place before the movement by which the presser member has been 45 brought into operative position has entirely ceased, the die will be struck a glancing blow and it is, therefore, desirable to prevent such operation of the machine and to insure that when the presser member strikes 50 the die it shall be moving in a direction substantially normal to the surface of the bed.

An object of the invention is to improve in this respect the operation of the machines of the type above described and to this end 55 the invention contemplates the provision in a machine of this type of means for preventing the continuation of the relative movement of the presser members by which they are brought into a selected operative 60 relation to each other during that relative movement by which the pressing operation is effected which shall operate to check the first mentioned relative movement before the last mentioned relative movement begins. 65

Another object of the invention is to provide means for effecting the purposes above set forth which shall be normally operative to maintain the presser members in what- 70 ever relation to each other they may be left after a movement either into or out of a selected operative relation.

In the illustrated preferred embodiment 75 the invention is shown as applied to a machine of the type disclosed in United States Letters Patent to Arthur Bates, No. 921,503, granted May 11, 1909, for improvements in machines for cutting out thin sheet material 80 such as upper leather for boots and shoes, in which a post or plunger mounted in bearings at one side of a stock supporting bed, for vertical reciprocation and for oscillation about its vertical axis, carries a presser 85 arm or presser member which may be swung over the bed into operative position above a movable die located over any part of the bed. In this machine when the laterally movable presser member has been brought into operative position over the die a clutch 90 is actuated through a starting device movable with the presser member whereby operative connections are effected with a driving pulley and a pressing operation is performed. Since the actuation of the clutch 95 takes place after the presser member has come into, or substantially into, the selected operative relation to the bed, which in the present construction will be the operative position over the die, and since the actuation of the clutch must precede the pressing operation, the clutch actuating movement of the starting device may conveniently be 100 utilized to control the operation of the

means for checking the lateral movement of the presser member over the bed before its movement toward the bed begins and in the preferred embodiment of the invention advantage is thus taken of this movement.

An important feature of the invention, therefore, is the provision in a machine of the class described of means controlled by the starting means for preventing the continuation of the relative movement by which the presser members are brought into a selected operative relation to each other during the relative pressing movement of said members.

Another important feature is the provision of means controlled by the starting means for checking the relative movement by which the presser members have been brought into a selected operative relation to each other before the relative pressing movement begins.

As hereinabove suggested, the means for checking the relative movement by which the presser members are brought into a selected operative relation to each other is preferably normally operative, and it is therefore essential that provision be made for rendering the means inoperative when it is desired to effect a relative movement of the members into or out of a selected operative relation.

In the illustrated preferred embodiment of the invention, the movement of the presser member over the bed is effected by hand, and the starting means is provided with a handle which may be grasped by the operator to effect such movement, the starting means being so constructed that depression of the same handle will serve to actuate the clutch. This arrangement of the starting means and the handle by which it is manipulated is that employed in the commercial machine and, in the illustrated embodiment, in order that the invention may be carried out and yet have the steps in the operation of the machine substantially like those in the operation of the commercial machine, provision has been made for a lateral movement of this handle by which the means hereinabove referred to, which may conveniently be called the braking means, is rendered inoperative as the handle is grasped by the operator and moved in the direction in which it is desired that the presser member shall move.

It will, therefore, be seen that another important feature of the invention is the provision in a machine of the class described of normally operative braking means which serves to prevent relative movement of the presser members other than their relative pressing movement and means for rendering said braking means inoperative which is actuated, preferably automatically, as the operator grasps the handle by which the

relative movement into or out of a selected operative relation is effected.

In another aspect, the invention may be said to comprise the provision in a machine in which the presser member is manually movable into and out of different operative relations to a stock supporting bed of means, preferably acting automatically, for preventing further movement of said member at either or each of the limits of its manual movement.

Other features and objects of the invention will be apparent from a consideration of the following description and claims taken in connection with the accompanying drawings, in which—

Figure 1 is a side elevation of a machine of the type known to the trade as the Clicking machine, having embodied therein the invention of this application; Fig. 2 is a detail plan, partly in section, showing the construction of the braking means and the means for rendering said braking means inoperative; and Fig. 3 is a detail section illustrating further the construction of the braking means.

The machine herein illustrated comprises a stock supporting bed 2 mounted upon a bracket 4 bolted to the main part of the frame 6 in which are formed bearings 8 and 10 for a vertical post or plunger 12 carrying a presser member 14 which is arranged to swing with the post 12 whereby it may be brought into operative position over a movable die 16 placed upon a selected portion 100 of the material 18 which is to be cut, after which a loose pulley 20 is clutched to a driving shaft 22 by suitable clutch mechanism not herein specifically illustrated and described whereby through suitable eccentric 105 connections with the post or plunger 12 the pressing operation is effected.

The parts thus far described may be substantially those in commercial use and do not specifically form features of the present 110 invention.

The braking means of this invention is preferably arranged to operate upon or through the post or plunger 12. The illustrated braking means is of the expanding 115 ring type, a split ring 24 being connected to the post or plunger 12 and expanding into engagement with the inner surface of the other brake member 26 which has a rearwardly extending portion 28 guided and 120 confined in a vertical slot 27 in an upstanding part 29 of the frame 6. The expanding ring 24 is supported in operative relation to the brake member 26 by a support comprising a sleeve 30 which is keyed to the 125 post 12 by a key 32 entering a vertical groove 34 in the post, whereby the sleeve is caused to turn with the post. The sleeve is also attached to the post to move vertically therewith. The sleeve 30 is provided 130

at its lower end with a flange 36 upon which the expanding ring 24 rests. The ring is caused to turn with the sleeve and post by a loose connection therewith comprising a lug 38 upon a member 40 rigidly attached to the sleeve or to its flange. The lug 38 enters a notch 42 in the expanding ring 24. A collar 43 screwed upon the upper end of the sleeve 30 above the brake member 26 confines the said member so that it moves vertically with the post 12 although it is prevented from turning therewith by the engagement of the extension 28 with the sides of the slot 27.

15 The ring 24 is maintained normally in its expanded condition by a screw threaded thrust pin 44 which is threaded into the ring upon one side of the split therein and has a bearing against the ring upon the other side 20 of the split. Attached to the thrust pin is an operating arm 46 against which bears one end of a spring 48 which is socketed at its other end in the flange 36, this flange being also slotted in this region to receive the arm 25 46. Pivotaly connected to the lower end of the arm 46 is a plunger 50 which is guided in an opening in a lug 52 depending from the flange 36. The spring 48 presses the arm 46 normally in the direction to cause 30 the ring to be expanded into engagement with the brake member 26 whereby the brake is normally operative. The plunger 50 is moved in the direction to release the braking means by mechanism now to be described.

35 In this machine, as in the commercial Clicking machine, the starting clutch is actuated through a lever 54 which is pivoted at 56 in the frame 6 and is connected by a rod 58 with a clutch tripping lever 60. The forward arm of the lever in this machine, as in the commercial Clicking machine, is provided with a swivel surrounding and concentric with the post 12 so that one part of the arm may swing with the presser member 40 45 14. In this machine the construction of the part 62 of the forward arm of the lever 54, which part travels with the presser member 14, has been modified and upon this part 62 has been mounted mechanism through which 50 the plunger 50 is operated. The presser member 14 is caused to swing with the part 62, when the handle 64 is grasped, by the engagement of one side of an opening in the part 62 with a pin 66 upon the presser member, the part 62 being free to move vertically 55 over said pin. The handle 64 is carried upon a member 68 which is provided with two slots 70 and 72 concentric with the opening in the member through which the pin 66 passes. The slots 70 and 72 receive pins 74 and 76, respectively, upstanding from the flat expanded portion of the part 62. Pivotally connected to the rear end of the member 68 is a link 78 connected at its other end 60 65 at 80 to the lower arm of the plunger actuating lever 82 fulcrumed at 84 in one member 86 of the swivel surrounding the post 12. The member 68 and handle 64 are maintained normally in their middle position by a spring 88 connected at one end to the rear 70 middle part of the member 68 and at its other end to the lug 90 upon the part 62. Vertical adjustment of the post 12 in the usual manner by the hand wheel 92 is provided for by extending the plunger engaging 75 portion of the lever 82.

75 The operation of this machine may be briefly described as follows:—Let it be assumed that the presser member 14 is at one side of the portion of the stock upon which the operator desires to place the die 16 and that the die 16 has been placed upon the selected portion of the stock. At this time the presser member is held in the position in which it has been left by the action of the 80 braking means hereinabove described, the ring 24 being normally expanded into engagement with the brake member 26, and the handle 64 is in mid position upon the presser member and upon the part 62 of the clutch 85 actuating lever. The operator now grasps the handle 64 to swing the presser member 14 into operative position over the die. As the presser member is held against lateral movement by the braking means the member 68 90 will be turned by the handle 64 about a center coinciding with the center of the opening which receives the pin 66 in one direction or the other. The direction in which the member 68 turns will depend obviously 95 upon the position of the presser member when the operator grasps the handle. If the presser member is to the right of the portion of the stock upon which the operator has placed the die, the member 68 will be 100 turned in a clockwise direction in Fig. 2, and vice versa if the presser member be to the left of the said portion of the stock. Turning of the member 68 in either direction will cause the link 78 to pull forward 105 the lower arm of the lever 82, thereby causing the upper arm to be moved rearwardly into engagement with the plunger 50. As the plunger 50 is moved to the left in Fig. 3 by the rearward movement of the upper arm 110 of the lever 82, it will turn the thrust pin 44 in the direction to permit the ring 24 to contract out of engagement with the brake member 26. The presser member 14 is therefore now free to move with the part 62 of the 115 clutch actuating lever 54 and will continue free to move therewith until it comes into operative position over the die when the operator will ordinarily check the movement of the handle 64, thereby again bringing it 120 to mid position and permitting the spring 48 operating through the arm 46 again to expand the ring 24 into engagement with the brake member 26 and stop the presser member in this position. The operator now 125 130

depresses the handle 64, thus depressing the forward arm of the lever 54 and actuating the clutch.

It will be noted that the application of the brake to the post 12 takes place before the actuation of the clutch and that the brake is automatically released as the operator starts to swing the presser member in either direction through the handle 64. It will be noted further that the braking means serves to prevent further movement of the presser member both as it comes into operative position over the die and again when the operator has moved it the desired distance out of operative position over the die. It will, therefore, be seen that an important advantage of the present construction is that the presser member will not be swung out of reach of the operator as he moves it from operative into inoperative position, no matter how rapidly it may be moving at the time when he lets go of the handle.

In the foregoing description of the operation of the machine reference has been made to checking the movement of the handle 64 as the presser member 14 comes into operative position over the die. This will be the usual procedure since the operator will keep hold of the handle in order to depress it to actuate the clutch. It will be understood, however, that such checking of the movement of the handle 64 is not necessary to cause the braking means to act to prevent the further movement of the presser member but that the operator may release the handle, if he desires, when the spring 88 will restore it to its mid position, thereby again permitting the braking means to act upon the post or plunger 12.

Having described my invention what I claim as new and desire to secure by Letters Patent of the United States is:—

1. A machine of the class described, having, in combination, presser members relatively movable into different operative relations to each other and relatively movable toward and away from each other to effect a pressing operation, and means for preventing the continuation of the first mentioned relative movement of the presser members during the relative movement by which the pressing operation is effected constructed to check the first mentioned relative movement before the relative pressing movement begins.
2. A machine of the class described, having, in combination, a bed, a presser member laterally movable over said bed into different operative relations thereto, mechanism for moving the presser member toward and away from said bed, and means, operating before the movement of the presser member toward the bed begins, to check the lateral movement of said member.
3. A machine of the class described, hav-

ing, in combination, a bed, a presser member movable over said bed into different operative relations thereto and movable toward and away from said bed to effect a pressing operation, and means for maintaining said presser member in whatever relation to the bed it is left.

4. A machine of the class described, having, in combination, a bed, a presser member manually movable over the bed into different operative relations thereto and movable toward and away from the bed to effect a pressing operation, and means for preventing further movement of the presser member over the bed when released by the hand of the operator.

5. A machine of the class described, having, in combination, a bed, a presser member manually movable over said bed into and out of different operative relations thereto, and means for preventing the further movement of said member at each of the limits of its manual movement.

6. A machine of the class described, having, in combination, a bed, a presser member manually movable over said bed into and out of different operative relations thereto, and means operating automatically to prevent further movement of said member at each of the limits of its manual movement.

7. A machine of the class described, having, in combination, a bed, a presser member manually movable over said bed into and out of different operative relations thereto, a handle to be grasped by the operator in effecting such manual movement, and means operated upon the release of said handle for preventing movement of said member beyond the limits of the manual movement.

8. A machine of the class described, having, in combination, a bed, a presser member manually movable over said bed into and out of different operative relations thereto, and means for preventing movement of said presser member out of operative position beyond the limit of its manual movement for this purpose.

9. A machine of the class described, having, in combination, a bed, a presser member manually movable over said bed into and out of different operative relations thereto and movable toward and away from said bed to effect a pressing operation, and means operating before the beginning of the movement of said presser member toward the bed for preventing its movement beyond the limit of its manual movement into operative position.

10. A machine of the class described, having, in combination, a bed, a die movable over said bed, a presser member manually movable over the bed into and out of operative position above the die wherever located on said bed, and means for preventing the

further movement of said member at each of the limits of its manual movement.

11. A machine of the class described, having, in combination, a bed, a die movable over said bed, a presser member manually movable into and out of operative position above said die wherever located on said bed, and means for preventing movement of said presser member out of operative position beyond the limit of its manual movement for this purpose.

12. A machine of the class described, having, in combination, a bed, a die freely movable over said bed, a presser member manually movable into and out of operative position above the die wherever located on said bed and movable toward and away from the die to effect the pressing operation, and means operating before the beginning of the movement of the presser member toward the die for preventing its movement beyond the limit of its manual movement into operative position.

13. A machine of the class described, having, in combination, presser members relatively movable into different operative relations to each other and relatively movable toward and away from each other to effect a pressing operation, starting means for controlling the relative pressing movement of the presser members, and means controlled by the starting means for preventing the continuation of the relative movement by which the presser members are brought into a selected operative relation during the relative pressing movement.

14. A machine of the class described, having, in combination, presser members relatively movable into different operative relations to each other and relatively movable toward and away from each other to effect a pressing operation, starting means for controlling the relative pressing movement, and means controlled by the starting means for checking the relative movement by which the presser members have been brought into a selected operative relation to each other before the relative pressing movement begins.

15. A machine of the class described, having, in combination, presser members relatively movable into different operative relations to each other and relatively movable in a direction transverse to the first movement to effect a pressing operation, braking means acting normally to prevent the first mentioned relative movement of said presser members, a handle arranged to be grasped by the operator for effecting such movement, and means for rendering said braking means inoperative automatically actuated as the operator grasps the handle.

16. A machine of the class described, having, in combination, a bed, a presser member manually movable over said bed into and out

of different operative relations thereto, a handle arranged to be grasped by the operator in moving the presser member over the bed, said handle being movable with said presser member and also movable relatively thereto, and means controlled by the relative movement of the handle to the presser member for preventing the further movement of said member at the limit of its manual movement.

17. A machine of the class described, having, in combination, a bed, a presser member manually movable over said bed into and out of different operative relations thereto, a handle to be grasped by the operator in effecting the manual movement of the presser member and arranged for movement with said member and also for movement relative thereto in two directions, means controlled by the relative movement of the handle in one direction for effecting the pressing movement of the presser member, and means controlled by the relative movement of the handle in the other direction for preventing the further movement of said member at the limit of its manual movement.

18. A machine of the class described, having, in combination, a bed, a presser member manually movable over said bed into and out of different operative relations thereto, braking means operating to hold the presser member normally against movement over the bed, a handle to be grasped by the operator in effecting the manual movement of the presser member, said handle being movable relatively to the presser member in the direction of the movement of said member over the bed and being yieldingly maintained in its mid position on said member, and means operated by the relative movement of the handle to the presser member caused by the initial resistance of the presser member to the manual movement for rendering the braking means inoperative.

19. A machine of the class described, having, in combination, a bed, a presser member manually movable over the bed into and out of different operative relations thereto, a handle to be grasped by the operator in moving the presser member over the bed, said handle being movable with the presser member and also movable relatively thereto in directions corresponding to the directions of movement of the presser member over the bed, means controlled by the relative movement of the handle to the presser member for preventing the further movement of said member at the limit of its manual movement, and means for yieldingly maintaining said handle in its mid position.

20. A machine of the class described, having, in combination, a bed, a presser member manually movable over said bed into and out

of different operative relations thereto, normally operative braking means for holding the presser member against movement over the bed, a handle arranged to be grasped by 5 the operator in effecting the manual movement of the presser member, said handle being movable with said presser member over the bed and movable relatively thereto to render said braking means inoperative, and 10 means for yieldingly maintaining said handle in that position in which it permits the braking means to remain operative.

21. A machine of the class described, having in combination, a bed, a presser member 15 manually movable over said bed into and out of different operative relations thereto, and means comprising an expanding ring yieldingly maintained normally in its expanded condition for preventing the further movement 20 of said member at each of the limits of its manual movement.

22. A machine of the class described, having, in combination, a bed, a presser member 25 movable over the bed into and out of different operative relations thereto, means comprising an expanding ring yieldingly maintained normally in its expanded condition for holding the presser member against movement over the bed, and means under 30 the control of the operator for rendering the holding means inoperative when such movement of the presser member is desired.

23. A machine of the class described, having, in combination, a bed, a presser member 35 movable over said bed into and out of different operative relations thereto, a post to which said presser member is attached mounted in bearings at one side of said bed for vertical reciprocation and for oscillation 40 about its vertical axis, and means for checking the movement of the presser member over the bed comprising an expanding ring, a brake member surrounding said ring and into engagement with which said ring is arranged to expand, one of said parts being carried by the post and the other by the machine frame, and means for expanding said ring.

24. A machine of the class described, having, in combination, a bed, a presser member 50 movable over said bed into and out of different operative relations thereto, a post to which said presser member is attached mounted in bearings at one side of said bed for vertical reciprocation and for oscillation 55 about its vertical axis, and means for checking the movement of the presser member over the bed comprising an expanding ring, a brake member surrounding said ring and 60 into engagement with which said ring is arranged to expand, one of said parts being carried by the post and the other by the machine frame, yielding means operating to expand said ring into engagement with 65 said brake member, and means under the

control of the operator for effecting the disengagement of the ring and the brake member.

25. A machine of the class described, having, in combination, a bed, a presser member 70 angularly movable over the bed into and out of different operative relations thereto, braking means for checking the movement of the presser member over the bed, and means moving with the presser member for 75 controlling the operation of the braking means at any angular position of the presser member.

26. A machine of the class described, having, in combination, a bed, a presser member 80 angularly movable over the bed into and out of different operative relations thereto, normally operative braking means for checking the movement of the presser member over the bed, and means movable with 85 the presser member for rendering the braking means inoperative at any angular position of the presser member.

27. A machine of the class described, having, in combination, a bed, a presser member 90 laterally movable over said bed into different operative relations thereto and movable toward and away from said bed to effect a pressing operation, braking means normally operative to maintain said presser member 95 against lateral movement, and means for rendering said braking means inoperative when it is desired to move the presser member over the bed.

28. A machine of the class described, having, in combination, a bed, a presser member 100 manually movable over said bed into different operative relations thereto and movable toward and away from said bed to effect a pressing operation, braking means normally 105 operative to maintain said presser member in whatever position over the bed it may be and means automatically operated as the operator starts to move the presser member for rendering said braking means inoperative.

29. A machine of the class described, having, in combination, a bed, a presser member 110 laterally movable over said bed into different operative relations thereto and movable 115 toward and away from said bed to effect a pressing operation, braking means normally operative to maintain said presser member in whatever position it may be stopped in its path of lateral movement, and means 120 automatically actuated as a laterally moving force is applied to the presser member for rendering said braking means inoperative.

30. A machine of the class described, having, in combination, a bed, a die freely movable over the bed, a presser member having a pressure surface area less than that of the bed, movable over the bed into operative position above the die wherever located on the bed and movable into and out of en- 130

gagement with the die, braking means normally operative to maintain said presser member in whatever position it may be stopped in its path of movement over the bed, and means automatically actuated as a laterally moving force is applied to the presser member for rendering said braking means inoperative.

In testimony whereof I have signed my name to this specification in the presence of 10 two subscribing witnesses.
